UNITED STATES PATENT OFFICE

130,686

DESIGN FOR A RESPIRATOR

William H. Lehmberg, Dudley, Mass., assignor to
American Optical Company, Southbridge,
Mass., a voluntary association of Massachu-
setts

Application February 21, 1941, Serial No. 99,201

Term of patent 14 years

To all whom it may concern:

Be it known that I, William H. Lehmberg, a citizen of the United States of America residing at Dudley, in the county of Worcester and State of Massachusetts, have invented a new, original, and ornamental Design for a Respirator, of which the following is a specification, reference being made to the accompanying drawing, forming a part thereof.

This application is a continuation in part of my copending application Serial Number D-90,329, filed February 17, 1940.

Fig. I is a front elevational view of a respirator embodying my new design;

Fig. II is a side elevational view of said respirator;

Fig. III is a rear elevational view of said respirator.

The characteristic features of the design are shown in full lines.

I claim:

The ornamental design for a respirator, substantially as shown and described.

WILLIAM H. LEHMBERG.
